DOWNDRAFT CARBURETOR

August H. Blattner, St. Louis County, Mo., assignor to Carter Carburetor Corporation, St. Louis, Mo., a corporation of Delaware

Application March 20, 1933, Serial No. 661,682

10 Claims.

(Cl. 261—41)

This invention relates to carburetors and more particularly to downdraft carburetors. The object of the invention is to provide a generally new and improved downdraft carburetor construction, capable of being produced by modern methods such as die casting.

5 A further object of the invention is to produce a carburetor construction of the downdraft type, constructed in such a manner as to avoid the 10 phenomenon of "percolation" which is such a well known source of trouble in downdraft carburetors.

Other objects of the invention will appear from the following description and accompanying 15 drawings, referring to which:

Figure 1 is a vertical sectional elevation of a carburetor constructed according to my invention.

Figure 2 is a sectional plan view of the carburetor shown in Figure 1, the section being taken 20 along the line 2—2 in Figure 1.

Figure 3 shows a plan view of the main venturi constructed according to my invention.

Figure 4 is a vertical sectional view of the main venturi shown in Figure 3.

25 The reference numeral 1 indicates the base or attaching flange member of a carburetor, having a flange 2 thereon by means of which it may be attached to the manifold of an internal combustion engine. While the manifold, which is dia- 30 grammatically indicated at 35, forms no part of this invention, it will be understood that present practice in the construction of internal combustion engines is to practically combine the intake and exhaust manifolds, at least at certain points, 35 for the purpose of heating the fuel mixture, so that the intake manifold and the carburetor above it are subjected to very high temperatures, particularly when the motor is slowed down or stopped after being operated at high speed for a 40 substantial period.

The base member of the carburetor including the flange 2 is preferably made of cast iron and carries the throttle valve 3, mounted on shaft 4 and controlling the mixing conduit 5. The main 45 venturi 6 is formed as a separate die casting, having a flange 7 which is mounted between two heat insulating gaskets 8 and 9 as indicated in Figure 1. The upper part of the mixing conduit 5 is cut away as indicated at 10 to prevent direct heat 50 transference to the main Venturi member. The upper part of the main venturi is also externally recessed as indicated at 11 to minimize the transfer of heat from this member to the intermediate body member 12 which is formed as a die casting, 55 preferably of zinc or aluminum. The primary venturis and the full reservoir or float chamber 13, as well as the main nozzle 14 are made integral with the casting 12 for convenience in manufacture, and for that reason the nozzle 14 cannot be 60 insulated from the remainder of casting 12.

The upper part of the carburetor comprises the member 15 which may be referred to as an air horn or air inlet member and which has the float chamber cover 16 formed integral therewith. The float chamber cover 16 also has formed integrally therewith a projection 17 extending downwardly into the float chamber 13 and having an opening therein to receive the pivot pin 18 of the float 19. The float valve 20 is of conventional construction except that it is mounted in a 10 needle seat 21, screwed into the same member on which the float itself is pivoted. By this construction the float and float valve may be removed as an assembly when the float chamber cover is removed.

15 It will be noted that the float chamber 13 is provided with substantially parallel walls 22, (Fig. 2) spaced just far enough apart to receive the float pivot pin 18 and the projection 17 so that no retaining devices are required to prevent the dis- 20 assembly of the pin 18 from the float mechanism.

The fuel is supplied to the float chamber through the inlet connection 24 and maintained substantially at the lever A—A by the float mechanism. The main nozzle 14 is mounted in an 25 inclined position to receive its fuel thru the main metering jet 25, which jet is controlled by a conventional metering rod 26, having a plurality of metering steps one of which is indicated at 27 to variably restrict the jet or nozzle 25 in accordance 30 with the requirements of the carburetor. The metering rod is connected to the rocker arm 28 by means of a loose fitting pin 29 and the rocker arm is operated by any suitable means such as a 35 connection to the throttle or to a suction operated piston. This operating means however, forms no part of this invention and is not shown. It may be stated however, that the rocker arm 28 is mounted on the rock shaft 30, carried in pillow block 31, and the float bowl vent 32 is carried at 40 a high point in the hollow pillow block to prevent fuel splashing out of the opening. A fuel supply conduit 33 extends upwardly through portions 1 and 12 of the carburetor body to a point above the fuel level and is connected to the main nozzle 45 34. A suitable inside vent 35 is provided at the upper end of the conduits 33—34.

The recessed portions 10 and 11, together with the heat insulating gaskets 8 and 9 function to 50 resist to a substantial extent the upward transference of heat from the flange 2 and the manifold to the float chamber 13 and the main nozzle 14. In case sufficient heat is developed to start a boiling action in the liquid fuel, small bubbles will 55 begin to form in the chamber 36 and the lower part of the main nozzle. The greater part of these bubbles will find their way out thru the conduit 34 and vent 35, thereby dissipating the lower boiling constituents of the gasoline and also 60

resisting the tendency of large bubbles to form and pass up thru the main nozzle 14, which would initiate what is known as percolation.

It is well understood that ordinary gasoline is a mixture of a large number of different hydrocarbons boiling at different temperatures and after the first 10 or 20% has been boiled off, the residue is what is known as weathered gasoline which will not boil under the temperature conditions to which the nozzle 14 and the float chamber 13 are subjected. The provision of the conduit 34 which leads directly upwardly from a point in the upper side of the nozzle 14, together with the provision of the vent 35 at the upper end of conduit 34 permits the escape of the lower boiling constituents, leaving weathered gasoline in the chamber 36 and nozzle 14 so that no percolation occurs.

The invention is not limited in details to the structure shown but may be modified in various respects as will occur to those skilled in the art and the exclusive use of all such modifications that come within the scope of the appended claims is contemplated.

25 I claim:

1. A downdraft carburetor having a base member for attachment to the manifold of an internal combustion engine, a fuel containing member mounted above said base member, a main Venturi member, having an outwardly extending flange member interposed between said base member and said fuel containing member, and means located both above and below the flange member for interrupting the transfer of heat.

35 2. In a downdraft carburetor, a base member having a mixing conduit, a main Venturi member having an outwardly extending flange mounted on said base member, said Venturi member having a portion projecting into said mixing conduit, the upper wall of said mixing conduit and the outer wall of said projecting portion being spaced apart to prevent direct transference of heat, and insulating gaskets mounted above and below said flange.

45 3. In a downdraft carburetor, a base member having a mixing conduit therein, a main Venturi member having an outwardly extending flange and being mounted on said first named member, said Venturi member having a portion projecting into said mixing conduit, the upper wall of said mixing conduit and the outer wall of said projecting portion being spaced apart to prevent direct transference of heat, an upper body member mounted above said Venturi member, and heat insulating gaskets separating said Venturi member from said upper and base members.

4. In a downdraft carburetor having a mixing conduit, a base member having an opening forming the lower part of said mixing conduit, a main Venturi member having an outwardly extending flange and being mounted on said first named member, said Venturi member having a portion projecting into said mixing conduit, an upper body member mounted above said Venturi member and having an opening forming the upper part of said mixing conduit, and heat insulating gaskets separating said Venturi member from said upper and base members, the wall of said mixing conduit and the outer wall of said projecting portion being spaced apart to prevent direct transference of heat.

5. In combination with an internal combustion engine, a manifold, a carburetor body member having a fuel reservoir and a fuel nozzle therein,

said nozzle being upwardly inclined and leading from said reservoir to a discharge outlet, said member having a conduit extending upwardly from a point in said nozzle terminating in a vent, and a downwardly extending idle conduit connected to said conduit below said vent, a flanged Venturi member mounted between said body member and said manifold, a portion of said flanged member being cut away to interrupt the transfer of heat from said manifold to said body member, and a pair of spaced insulating gaskets inserted between another portion of said Venturi member and said body and said manifold for further interrupting said transfer of heat.

6. A downdraft carburetor having a flanged base member for attachment to the intake manifold of an engine, a substantially cylindrical mixing conduit in said flanged member, the upper end of said mixing conduit being slightly enlarged, a flanged Venturi member mounted above said first named member and having a venturi projecting into the enlarged portion of said mixing conduit, the enlargement of said mixing conduit forming a clearance between the base member and the venturi, thereby preventing the direct transfer of heat from said lower flanged member to said upper flanged member, and heat insulating gaskets on each side of said flanged Venturi member for interrupting the transfer of heat from the manifold to the carburetor.

7. A downdraft carburetor comprising upper and lower body members separated by a Venturi member, said Venturi member extending substantially into at least one of said upper and lower body members and having a surrounding flange 35 extending between said upper and lower body members, the extreme ends only of said Venturi member being in substantial contact with said upper and lower body members, and insulating gaskets between said flange and each of said upper and lower body members.

8. A downdraft carburetor comprising upper and lower body members separated by a Venturi member, said Venturi member extending substantially into said upper and lower body members and having a surrounding flange extending between said upper and lower body members, the extreme ends only of said Venturi member being in substantial contact with said upper and lower body members, and insulating gaskets between 50 said flange and each of said upper and lower body members.

9. In a structure of the class described, a carburetor body member having a fuel chamber therein, a part for direct association with an internal combustion engine, a metallic Venturi member having a flange between said body member and said part, and a pair of spaced heat insulating gaskets for resisting the direct transfer of heat from said part to said carburetor.

10. In a carburetor, a base member for direct association with the body of an internal combustion engine, there being a conduit in said base member and the upper portion of said conduit being slightly enlarged, a flanged member mounted above said base member and having a venturi projecting into the enlarged portion of said conduit, there being clearance space between the wall of said conduit and said venturi for preventing the direct transfer of heat from said base member to said upper flanged member, and heat insulating gaskets on each side of said flanged member for interrupting the transfer of heat from said base member to said flanged member.

AUGUST H. BLATTNER. 75
